UNITED STATES PATENT OFFICE.

NELSON F. HOWARD AND COLONEL L. HOWARD, OF FAIRFIELD TOWNSHIP, INDIANA.

MOLD FOR CONCRETE POSTS.

Application filed July 2, 1921. Serial No. 482,203.

To all whom it may concern:

Be it known that we, NELSON F. HOWARD and COLONEL L. HOWARD, citizens of the United States, residing in Fairfield Township, in the county of Tippecanoe and State of Indiana, have invented a new and useful Mold for Concrete Posts, of which the following is a specification, reference being had to the accompanying drawings, and to the letters and figures of reference marked thereon.

The invention relates to a mold whereby concrete fence posts may be molded in upright position, and it has reference more particularly to a sectional mold for monolithic concrete corner posts that have fence wire tightening appliances thereon.

An object of the invention is to provide an improved post mold of such construction as to be adapted to be compactly hauled or carried from place to place in knock-down condition, and adapted also to be quickly set up for use where a post is required.

Another object is to provide an improved mold for monolithic concrete posts which shall be so constructed as to be adapted for molding either a right-hand or a left-hand post adjoining a roadway with fence wire tightening appliances on the posts that shall not project and be obstructive at the side of a roadway.

A further object is to provide an improved post mold whereby the monolithic concrete post may be rapidly moulded with anchoring devices accurately set therein, which mold shall be so constructed as to permit of its being readily removed from the molded post and the anchoring devices.

A still further object is to provide a sectional post mold which shall have few and simple parts and no small parts liable to become separated and lost when the mold is not in use and stowed away, which mold shall be of such construction as to be durable and economical in use.

With the above mentioned and other objects in view the invention consists in a post mold having mold sections hinged together and foldable, the mold sections being novel and having novel parts incorporated therein; and, the invention consists also further in the parts and combinations and arrangements of parts as hereinafter particularly described and further defined in the accompanying claims.

Referring to drawings,—Figure 1 is a per-

spective view of a fence post with wire fencing thereon, illustrating particularly the type of post which the improved mold is designed for molding; Fig. 2 is a fragmentary horizontal section illustrating the manner in which a journal boxing for the winding shaft of the post is arranged in the mold and embedded in the post; Fig. 3 is a fragmentary horizontal section illustrating the manner of arranging a power worm boxing in the mold so as to be embedded in the post; Fig. 4 is a fragmentary horizontal section of the post illustrating the arrangement of the power worm which is mounted in a boxing embedded in the post, the winding shaft being also illustrated in connection therewith in one of the two positions in which it may be arranged relatively to the post; Fig. 5 is a fragmentary sectional detail of the winding shaft and its center pin; Fig. 6 is a side elevation of the improved post mold; Fig. 7 is an elevation showing the inward bracing corner of the mold; Fig. 8 is a top view of two of the mold sections folded together and slightly tilted over from normal position; Fig. 9 is a top plan of the improved mold ready for use; Fig. 10 is a horizontal section of the mold on the line X—X in Fig. 6; Fig. 11 is a perspective view of the mold folded for transportation or storage; Fig. 12 is a fragmentary perspective view illustrating the manner of detachably connecting two sections of the mold together; and Fig. 13 is a fragmentary sectional detail of fastening devices for mold sections.

Similar reference characters in the different figures of the drawings indicate corresponding elements or features of construction herein referred to in detail.

The type of post that the improved mold is designed to produce comprises a concrete foundation 1 which is made in an excavation in the ground and has a corner portion 2 to support a winding shaft. The post comprises also a column 3 having vertical front or face sides 4 and 5 and inclined rear or brace sides 6 and 7. The corner portion 2 of the foundation has a center pin 8 fixed therein which is adjacent either to the side 4 or the side 5 of the column as may be desired and it guides a winding shaft 9 for tightening and securing wire fencing to the post, the upper portion of the shaft being guided in a bearing or boxing 10 having a shank 11 connected to a base anchor 12.

which is embedded in the column. The shaft 9 has a gear wheel 13 fixed thereto which is engaged by a worm 14 that may be operated to turn the shaft. The worm is 5 mounted in a boxing 15 which has a base anchor 16 that is embedded in the column. The boxing has ears 17 and 18 provided with screw bolts 19 and 20 whereby to hold the boxing in the post mold until the boxing be- 10 comes embedded in the post. The base anchors 12 and 16 may be arranged in the post either as shown or in relatively inverted positions as may be required to correspond with the determined position of the center 15 pin 8, in deciding whether to produce either a right-hand or a left-hand post. The arrangement of the fencing 21 and 22 in connection with the post will be readily understood.

20 The improved post mold comprises two front side form sections 23 and 24 and two rear side form sections 25 and 26. Each form section has a straight bottom or base portion 27 designed to stand upon the foundation 1, and each section has an edge 28 that is at right angles or vertical relatively to base portion, and an inclined edge 29 that extends at an acute angle from the base portion of the section. The mold sec- 25 tions preferably are composed of wood which may be coated with waterproof sub- stance. The section 23 has a cleat 30 fixed to the outer side thereof on the broader portion of the section, and a shorter cleat 30 31 on a narrower portion of the section, the section preferably having also additional cleats thereon, all the cleats being horizontal or parallel to the base bottom 27 of the section. The section 24 is likewise provided 35 on its outer side with cleats 30' and 31'. The mold section 25 is arranged with its right angular or vertical edge adjacent to the inclined edge of the section 23, the section 25 standing at an inclination. The section 25 is provided on its outer side 40 with cleats 32 and 33 that are arranged so that one end thereof shall be in connection with the cleats 30 and 31 respectively and which extend therefrom upwardly to the inclined edge 29 of the section 25. The other rear mold section 26 is similarly pro- 45 vided with inclined cleats 32' and 33' that are arranged to be connected at one end with the cleats 30' and 31' respectively, and at their opposite ends with the cleats 32 50 and 33 respectively. Strap hinges 34 are secured to the cleats 30 and 31 and to the cleats 32 and 33 whereby the sections 23 and 25 are hinged together; and the sec- 55 tions 24 and 26 are similarly hinged together by means of strap hinges 34' se- 60 cured to the cleats 30' and 31' and also to the cleats 32' and 33', the section 26 stand- 65 ing in inclined position with its right angled edge adjacent to the inclined edge of the

section 24 and its inclined edge adjacent to the inclined edge of section 25. Such arrangement of hinges insures close corner connections of the mold sections and permits the sections to be folded back each 70 to the other for compactly carrying the sections.

The vertical edges of the sections 23 and 24 are detachably connected together, preferably by means of hinge hasps comprising strap plates 35 secured to the cleats of one section and hasp plates 36 hinged to the strap plates and having slots 37 therein, the hasp plates being detachably secured to the cleats of the adjacent mold section, 75 preferably by means of screw shanks 38 inserted in the cleats and having head portions 39 that are received through the slots and turned against the hasp plates. The inclined edges of the sections 25 and 26 are 80 detachably connected together by means of hinge hasps having strap plates 35' secured to the inclined cleats on one of the sections and hasp plates 36' detachably connected to the inclined cleats on the adjacent section 85 in the manner above described. This arrangement of the cleats permits the parts of the hinge hasps to lie flat on the cleats and the hinge pins of the hasps to be in alignment each with the other.

The front sides 23 and 24 are provided with guides whereby to set the mold accurately with respect to the center pin 8, the lower portion of the section 23 preferably having a guide strip 40 secured thereto and the section 24 having a similar strip 41 secured thereto, the ends of the strips that are adjacent to the vertical edges of the sections having notches 42 and 43 therein, one of the notches receiving the center pin 8, depending on the position the winding shaft is to be arranged relatively to the vertical corner of the post, whether right-hand or left-hand. The upper portions of the form sections 23 and 24 have slots 44 and 45 therein extending from the vertical edges of the sections respectively to receive the shank 11 of the shaft bearing 10 to hold the base anchor 12 in proper position when filling the mold with concrete, the slots preferably being immediately above the upper cleats on the sections, and the sections preferably are provided with strengthening cleats 46 and 47 respectively that are arranged above the slots. At suitable positions the sections 23 and 24 have holes 48 and 49 therein respectively to receive the screw bolts 19 and 20 respectively whereby to support the boxing 15 in proper position while filling the mold with concrete.

In practical use the mold is set up upon the foundation 1 after the foundation is made and the concrete sufficiently set to support the post column, the mold being guided 130

- against the center pin 8 as above indicated, the sections of the mold being connected together as shown. The devices relating to the winding shaft are arranged in place in 5 the mold as described, after which the mold is filled with concrete which when sufficiently set permits the mold sections to be removed, which is accomplished readily after first manipulating the hasps and their connections. It will be understood that the sections 10 23 and 24 can be readily withdrawn from the shank 11 and that the screw bolts 19 and 20 are to be removed to permit the mold sections to be withdrawn from the box- 15 ing 15. After the mold sections are removed the sections that are hinged together are folded back and the two pairs may be placed together and connected together by means of the hasps and devices 39 as indicated in Fig. 8, the general arrangement of 20 the four sections being indicated in Fig. 11 so that the mold may be conveniently handle and carried, or stowed away for future use.
- 25 Having thus described the invention, what is claimed as new is:—
1. A concrete post mold including two front mold forms and two rear mold forms having each an inner plane face and a straight bottom, each form having one edge that is perpendicular to the bottom and one edge inclined relatively to the bottom of the form, the inclined edge of each front form and the perpendicular edge of an adjacent rear form being hinged together, the perpendicular edges of the front forms being detachably connected together, and the inclined edges of the rear forms being detachably connected together.
  2. A concrete post mold including two front side mold forms connected together at one edge thereof and extending each from the other at right angles, the lower portion of each form having a guide shoulder on the outer side thereof an in proximity to the adjacent form, and two rear side mold forms connected together and also connected respectively to the opposite edges of the front side mold forms.
  3. A concrete post mold including four upright mold forms connected one to another, two of the forms having vertical edges respectively detachably connected together and each of the two having a transverse slot therein extending from the vertical edge thereof and in proximity to the top of the form, each of the two forms having also a guide on the outer side thereof adjacent to the bottom of the form, the guides being adapted to co-operate with a pin to locate the mold.
  4. A concrete post mold including four mold sections having each a straight base bottom and a joint edge on a right angle to the bottom and also a joint edge on an acute
- angle to the bottom, means to connect the right-angled edges of two of the sections together, means to connect the acute-angled edges of the remaining two sections together, means to connect the right-angled edge of 70 one of the second-mentioned two sections to the acute-angled edge of one of the first-mentioned two sections, and means to connect the right-angled edge of the remaining one of the second-mentioned two sections to 75 the remaining one of the first-mentioned two sections.
5. A concrete post mold including four upright mold forms connected one to another, two of the forms having vertical edges respectively detachably connected together and each of the two having a guide on the outer side of the lower portion thereof and adjacent to the vertical edge to co-operate with a fixed pin to locate the mold, each of the 80 two forms having a transverse slot therein extending from the vertical edge thereof and on one and the same horizontal plane in proximity to the top of the form, each of the two mold forms having also a hole to 85 receive an anchoring device support adjacent to the vertical edge of the form and on one and the same plane between the guide and the slot.
6. A concrete post mold including two upright front mold forms having each a vertical edge and an inclined edge, the forms being arranged at right angles each to the other with their vertical edges together, a plurality of cleats horizontally arranged on the outer side of one of the mold forms and secured thereto and having a hinged hasp secured thereto adjacent to the vertical edge of the form, a plurality of cleats horizontally arranged on the outer side of the other of the 95 mold forms and secured thereto and provided with devices to secure the hasps detachably thereto, two rear mold forms having each an inclined edge arranged each adjacent to the other and having also a plurality of cleats on the outer side thereof extending downwardly from the inclined edge and secured to the form, the rear mold forms leaning on the inclined edge of the front mold forms respectively, hinges connecting the lower ends of the inclined cleats to the cleats on the front mold forms respectively, and hinged hasps detachably connecting the upper ends of the inclined cleats on one of the rear mold forms to the upper ends of 100 the cleats on the other of the rear mold forms.
